UNITED STATES PATENT OFFICE

102,270

DESIGN FOR A CRUCIFIX OR THE LIKE

Theresa Freske, Minneapolis, Minn.

Application July 17, 1936, Serial No. 63,909

Term of patent 3½ years

To all whom it may concern:

Be it known that I, Theresa Freske, a citizen of the United States, residing at Minneapolis, in the county of Hennepin and State of Minnesota, have invented a new, original, and ornamental Design for a Crucifix or the like, of which the following is a specification, reference being had to the accompanying drawing, forming a part thereof, wherein

Fig. 1 is a front perspective view of a crucifix or the like showing my new design, and

Fig. 2 is a rear perspective view of the same.

Fig. 3 is a sectional view taken longitudinally through the crucifix.

I claim:—

The ornamental design for a crucifix or the like, substantially as shown.

THERESA FRESKE,
